ROLLING MILL

Jeremiah W. O'Brien, 457 Morrison Drive,
Mount Lebanon, Pittsburgh 16, Pa.

Filed July 23, 1962, Ser. No. 211,531

Claims priority, application Great Britain, Dec. 21, 1961,

8 Claims. (Cl. 72—248)

This invention relates to rolling mills and is more particularly concerned with combination mills, which can be used either with different roll arrangements, such as four-high or two-high. Thus, for example, in some circumstances it is desirable to have a four-high plate mill which is capable of conversion for use as a two-high slabbing mill.

According to the present invention there is provided a rolling mill comprising a pair of fixed spaced apart housings adapted to alternatively receive a first roll arrangement consisting of a given number of rolls or a second roll arrangement consisting of a number of rolls greater than said given number, windows in said housings into which said two roll arrangements are alternatively received, the aggregate diameters, that is the sum of the diameters, of said second roll arrangement exceeding the aggregate diameters, that is the sum of the diameters, of said first arrangement, roll adjusting means mounted in said housings, bearing-chock assemblies mounted on the ends of said rolls, the length of the rolls of said first roll arrangement being such that their bearing-chock assemblies are offset toward the center of said mill relative to said roll adjusting means, a filler beam received in said window when said first roll arrangement is being employed carrying the bearing-chock assemblies of one of said rolls of said arrangement and transmitting the rolling loads of said roll to said roll adjusting means.

When the rolls of the four-high mill are wider than those for the two-high mill, as for example when the mill is to roll plate and to roll ingots to slabs, there arises the difficulty of accommodating the mill to both widths. One solution is to render one of the housings movable relative to the other, but this results in a complicated and costly design and in increased time for changeover from one type of mill to the other.

According to the present invention there is further provided a mill having a pair of relatively fixed housings each having sides defining a window for reception of two or more roll bearing-chock assemblies, the housing sides presenting bearing faces, for lateral support of bearing-chock assemblies, of greater width than the length of a roll neck whereby a pair of rolls each of a first length are receivable between the housings with the parts of the bearing-chock assemblies surrounding the necks at a first inward position in the housings to provide a two-high configuration or more rolls of a greater length than the spacing between the housings are receivable by the housings with the parts of the bearing-chock assemblies surrounding the necks at a second outward position in the housings to provide a roll arrangement of more than two-high configuration, the profile of the face of each housing side directed toward the other housing presenting a recess adjacent the zone of the roll bite whereby the roll arrangement of more than two-high configuration with rolls of greater length may work material of greater width than the spacing of the housings.

2

In order that the present invention may be well understood there will now be described an embodiment thereof, given by way of example only, reference being had to the accompanying drawings in which:

5 FIGURES 1 and 2 are part sectional elevation of a mill housing having respectively a two-high and a four-high roll arrangement, with the rolls at maximum separation;

FIGURES 3 and 4 are end elevations of the housings of FIGURES 1 and 2 respectively with the rolls at minimum separation;

FIGURE 5 is a horizontal section taken on line V—V of FIGURE 6 through the lower slabbing roll, when in position in the housings;

15 FIGURE 6 is a section on the line VI—VI of FIGURE 5;

FIGURE 7 is a section on the line VII—VII of FIGURE 9;

20 FIGURE 8 is a section on the line VIII—VIII of FIGURE 9; and

FIGURE 9 is an elevation of part of the two-high mill with the rolls separated.

Referring to the drawings, the combination mill has two housings 12, 13 which are secured together at a fixed separation appropriate to the widths of the plate mill rolls (160 inches, in the present instance). The two housings 12, 13 are similar to each other and each has a similar window 14 for the reception of the roll chocks. The housings 12, 13 and their windows 14 are appropriate to a four-high plate mill.

FIGURES 2 and 4 show the arrangement when the combination mill is used as a four-high plate mill. In this instance, in the windows of each housing 12, 13, there are in order, a bearing-chock assembly 15 for the lower back-up roll having an opening 16 for the back-up roll bearing, a bearing-chock assembly 17 for the lower work roll, having an opening 18 for the work roll bearing, a bearing-chock assembly 20 for the upper back-up roll, the bearing of which is received in the opening 21, and a bearing-chock assembly 22 for the upper work roll which is received in the opening 23. The upper work roll chock 22 is received, in known fashion, within a recess 22a in the upper back-up roll chock 20. As usual, a screw 24 engages against the top of chock 20 and a pair of hydraulic jacks 25 are arranged in a vertical passage within chock 17, one such jack 25 being shown in FIGURE 4, so as to engage between chock 17 and chock 22 and thereby to open the roll gap when the screw 24 on each housing is withdrawn. Hangers 19 engage beneath shoulders formed in chock 20 and are connected to a cylinder 19a mounted on top of the mill for urging the chock 20 against screw 24.

When the mill is to be converted to a slabbing mill having rolls narrower than those of the four-high plate mill (119 inches in this instance), the chocks 15, 17, 20, 22 and their rolls are removed and replaced by chocks for the two slabbing rolls 26, 27. The chocks for the rolls 26, 27 are shown at 30, 31 in FIGURE 1 and it will be seen that they occupy approximately the same positions in the windows 14 as did the chocks 17, 22 for the work rolls of the four-high mill. The space within the windows 14, previously occupied by the back-up chocks 15, 20 are occupied by window-fillers 32, 33 which take the form of beams bridging the two housings 12, 13. Beam 32 lies in the windows 14 between the housings

and the chocks 30 for the lower roll 26, while the beam 33 is interposed between the upper chocks 31 and the screws 24.

The hangers 19 engage beneath shoulders on the upper roll chocks 31 and operate to keep beam 33 in contact with the screws.

Because the slabbing mill rolls 26, 27 are narrower than the plate mill rolls, the center lines of the chocks 30, 31 for each roll 26, 27 are, perforce, arranged inwardly of the center lines 37 (FIGURE 5) of the two housings 12, 13. For this purpose, housings 12, 13 have, on each side of the windows 14, integral extensions 40 projecting inwardly towards each other and effectively enlarging the width of the housings at the windows. These extensions 40, which increase the lateral support for the rolls 26, 27, are discontinued at 41, in the region of the roll gap, in order to prevent obstruction of the full width of the roll gap during the use of the mill for rolling plate. As will be seen in FIGURE 5, the chocks 30, 31 each have overhanging extensions 42, in order to enlarge the areas of support given by the housings to the chocks. The rolls 26, 27 are held in axial position by fingers 43, which are formed integrally with the extensions 42 and which are slidably held between the housing 12 and removable keeper plates 44.

As before mentioned, and as shown in FIGURE 5, the chocks 30, 31 project into the space between the two housings 12, 13 and are displaced from the center lines 37 of the housings. However, proper lateral support is provided by the housing extension 40 and the necessary vertical support is given to the bearings by the beams 32, 33 which contact the chocks 30, 31 respectively over their entire length in the axial direction.

It has already been stated that the extensions 40 of the housings 12, 13 are discontinued in the region of the roll gap. When the mill is being operated as a four-high plate mill, the opposite edges of the plate pass unrestrictedly through the openings formed in the extensions 40. When the mill is to be used for rolling slab, a portion of lateral support for roll 27 is supplied in the region of the roll gap by swinging the removable extension pieces 45 about their vertical pins 46 from the dashline position shown in FIGURE 5 to the full line position shown thereof. Although not shown the extension pieces may be latched to the housings by latching means. Each extension piece 45 is hook-like and is enabled to withstand the lateral loads applied to its by the chocks 30, by virtue of the engagement of a shoulder 47 of the hooked part with a corresponding shoulder 47a on the housing.

The housings 12, 13 additionally carry, on each side of the roll gap, a number of feed rolls 48 which form a part of the roller tables on each side. Although FIGURES 5 and 7 show only three such feed rollers 48, if desired, the mill may be arranged to carry more such feed rollers.

As will be appreciated, the combination mill illustrated in the drawings is capable of being converted, without undue hold-up of production, from a four-high plate mill to a two-high slabbing mill, the rolls in the latter case being narrower than those in the former case. Additionally, when used as a slabbing mill, the rolls are given adequate support both vertically and horizontally at right angles to the axes of the rolls, although the center lines of the chocks are displaced from the center lines of the housings.

In accordance with the provisions of the patent statutes, I have explained the principle and operation of my invention and have illustrated and described what I consider to represent the best embodiment thereof. However, I desire to have it understood that within the scope of the appended claims, the invention may be practiced otherwise than as specifically illustrated and described.

I claim:

1. A rolling mill comprising a pair of fixed spaced

apart housings adapted to alternatively receive a first roll arrangement consisting of two rolls or a second roll arrangement consisting of four rolls, windows in said housings into which said two roll arrangements are alternatively received, the aggregate diameters of said second roll arrangement exceeding the aggregate diameters of said first arrangement, roll adjusting means mounted in said housings, bearing-chock assemblies mounted on the ends of said rolls, the length of the rolls of said first roll arrangement being such that their bearing-chock assemblies are offset toward the center of said mill relative to said roll adjusting means, a filler beam received in said windows when said first roll arrangement is being employed to carry the bearing-chock assemblies of one of said rolls of said first arrangement and transmitting the rolling loads of said roll adjusting means.

2. A rolling mill comprising a pair of fixed spaced apart housings adapted to receive a first roll arrangement consisting of a given number of rolls of a first aggregate diameter, windows in said housings into which said first roll arrangement is received, roll adjusting means mounted in said housings, bearing-chock assemblies mounted on the ends of said rolls, the length of the rolls of said first roll arrangement being such that their bearing-chock assemblies are offset toward the center of said mill relative to said roll adjusting means, a filler beam received in said windows when said first roll arrangement is in place for carrying the bearing-chock assemblies of one of said rolls of said first arrangement and serving to transmit the rolling loads of said roll to said roll adjusting means, the first roll arrangement and beam being removable and replaceable by a second roll arrangement of greater aggregate diameter than the first roll arrangement, the bearing-chock assemblies of one roll of said second arrangement serving to transmit the rolling load of said one roll to the roll adjusting means.

3. A rolling mill according to claim 2 in which each housing is recessed in the region of the roll bite of the second roll arrangement to provide a wider spacing between the housings whereby when the rolls of the second arrangement are of a greater axial length than the normal spacing between the housings, material of a greater width than the normal spacing can be worked.

4. A mill having a pair of relatively fixed spaced-apart housings each having sides defining a window for reception of two or more roll bearing-chock assemblies, the housing sides presenting bearing faces, for lateral support of bearing-chock assemblies, of greater width than the length of a roll neck whereby a pair of rolls each of a first length are receivable between the housings with the parts of the bearing-chock assemblies surrounding the necks at a first inward position in the housings to provide a two-high configuration or more rolls of a greater length than the spacing between the housings are receivable by the housings with the parts of the bearing-chock assemblies surrounding the necks at a second outward position in the housings to provide a roll arrangement of more than two-high configuration, the profile of the face of each housing side directed toward the other housing presenting a recess adjacent the zone of the roll bite to provide a wide space between the housings whereby the roll arrangement of more than two-high configuration with rolls of greater length may work material of greater width than the normal spacing of the housings.

5. A mill having a pair of relatively fixed spaced-apart housings each having sides defining a window, a pair of rolls located between the housings, the necks being received by bearing-chock assemblies in the windows, the opposed faces of each window being of greater width than the length of a roll neck, the face of each housing side directed toward the other housing being profiled to define a recess in the region of the bite to provide a locally increased spacing between the housings whereby when rolls of a greater axial length than the normal spacing between

the housings are mounted in the mill material of a greater width than the normal spacing may be worked, and the bearing-chock assemblies engaging window filling means engaging said housing windows.

6. A mill according to claim 5 in which each housing side includes a projection extending toward the other housing, a surface of each projection providing a support surface for a bearing-chock assembly of a roll of the first length, the projection being interrupted to define the recess.

7. A mill according to claim 6 including displaceable means on each housing side which in a first position lies in the recess to reduce the recess and in a second position lies clear of the recess.

8. A mill according to claim 5 in which the bearing-chock assembly at one end at least of each roll has flanges each received by a recess in a housing side to locate the bearing-chock assembly axially.
